CLAIM

The ornamental design for a wall plaque, as shown and
described.

DESCRIPTION

FIG. 1 is a front elevational view of the wall plaque
showing my new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof; and,

FIG. 7 is a perspective view thereof.

The legible matter shown in broken lines in FIGS. 1 and
7, is for illustrative purposes only and forms no part of
the claim.

FIG. 1

FIG. 2

FIG. 3

FIG. 4

FIG. 5

FIG. 6

FIG. 7
